METALLIC CHURNS AND BUTTER KNEADERS
HAVING NO KNEADING ROLLERSFernand Jean Joseph Julien Henrard, Remicourt,
Belgium, assignor to Ecrèmeuses Mélotte, Société Anonyme, Remicourt, Belgium, a Belgian
companyApplication July 14, 1945, Serial No. 605,083
In Belgium July 20, 1944

2 Claims. (Cl. 259—81)

1

My invention relates to metallic churning and butter-kneaders without rollers which are especially designed to be used at a farmstead.

Different types of metallic churning and butter-kneaders of cubical or conical shape (two cones united at their base) have heretofore been suggested, as those appliances possess a large capacity and have been designed in order to be used in industrial dairies. They perhaps possess advantages in this kind of industry, but are not suitable if they are reduced to the usual dimensions compatible with employment at farmsteads.

It is also well-known that the means which farmers employ to produce butter of good quality are not so numerous as those which milk industrialists employ.

An object of the invention is to offer to the farmers a metallic churn and butter-kneader without kneading rollers, the conditions of hygiene and of manipulation of which have been considerably improved in comparison with the churning and butter-kneaders now in use.

Another object is to permit varying, while modifying the apparatus as little as possible, the capacity of these latter which is indispensable for this kind of user and important in view of an economical manufacture in large quantities.

The invention also makes possible the production of butter with the methods at present in use in farmsteads and in this way does not complicate an operation which should be as easy and as practical as possible, while at the same time permitting the production of butter of the best quality.

According to the invention, this churn is essentially characterized by two parallel bottoms and by a body made from one single sheet, bent and curved according to three similar curves.

In the practical embodiment of the invention, the two extremities of this sheet do not rejoin each other after being bent, the spacing of these extremities corresponding to the width of the opening of the churn. This opening is preferably closed by a removable cover, which is bent according to the same curvature as the wall which it is intended to close.

The body of the churn can have the shape of an equilateral triangle, the three equal sides of which are preferably connected by a rounded profile.

Other advantages and especially an increase of the rotational or running speed and a more heavy churning can be obtained by providing a body possessing three partitions which have each a profile of cycloidal shape, the three cycloidal

profiles being preferably connected to each other by three plane faces which form an angle with the tangent drawn to the extremity of the cycloidal profiles.

The cycloidal curves occupy, with regard to the center of rotation of the churn, such a position that all the points of these curves deviate more and more from the center of rotation from their origin to their extremity.

10 The accompanying drawings illustrate churning according to the present invention.

Figure 1 is a front view of a churn,

Figure 2 is a section according to line C—D in Fig. 1,

15 Figures 3, 4, 5, 6 represent the elements which can be used for the making of such a metallic churn, and

Figure 7 illustrates the operation of this type of apparatus.

20 Figures 1 to 7 refer to a churn which comprises:

A body 1 made from one bent and curved sheet (Figs. 1 and 4);

25 A removable cover 3 (Fig. 6) which covers the opening 7 formed between the extremities 2 of the bent sheet 1; and

Two pressed bottoms 9 and 10 which are parallel and of a concave interior form.

The profile given to the body 1 is that of a cycloidal curve. These partitions, which are three in number and begin at 11, are isochrone, that is to say that unequal arches of one and the same cycloid are run through in equal times; moreover, the cycloid is the curve of the most rapid descent between two given points. These fundamental features of cycloidal curves show that liquids which glide down on such a profile are animated thereby by movements which give rise only to minimum efforts of friction in compari-

35 son with any other curvilinear or rectilinear profile. In consequence, as there exists a minimum friction between the walls of the churn and the cream, this latter is only very little drawn into the rotational motion communicated to the churn.

40 These frictions are still more reduced by the position which is occupied by the three cycloidal sections with regard to the center of rotation of the churn. As a matter of fact, all points of these cycloidal profiles deviate more and more from the center of rotation O of the churn from the origin of the curve at 11 to its extremity at 12 (Fig. 7).

45 Two features are consequently to be considered as they contribute to diminish the risk of the cream being carried away by the walls of the

churn and the rotational speed, and the impact of the cream against the three plane faces 13 (Fig. 7), can therefore be considerably increased.

The three cycloidal profiles are connected to each other by three plane faces 13 which form an angle with the tangent drawn to the extremity 12 of the cycloidal profiles.

These plane faces 13 play a part in that they progressively remove the cycloidal walls from the center of rotation of the churn in order to permit of a more vigorous and heavy churning of the cream and to make the operation of the kneading more efficacious.

During the churning and at each revolution of the churn, the cream undergoes three shocks brought about by its meeting the three plane faces 13. When the butter is finished, the churn is stopped and the buttermilk is drawn off, then the butter-granules are washed with cold water and then the water is removed.

The operation of kneading is then commenced for which operation the speed of rotation of the churn remains unchanged. The mass of butter-granules is lifted up and kept back successively by the three plane faces 13 (Fig. 7) until their inclination, with regard to the vertical, lets the butter fall from position B to position B¹ (Fig. 7) which when falling falls back on the projections 14 (Fig. 7) where it is kneaded to remove any remaining water.

The butter is kneaded in this way three times at each revolution (Fig. 7). It follows therefrom that in the course of a few revolutions all the butter which is distributed over the whole length of the churn, and that in an almost uniform way, is entirely kneaded and each time when butter in the churn falls on the projections 14, a certain quantity of water, retained by the butter, is removed, which progressively allows small butter-granules to approach each other and to stick together. Due to the fact that the butter is distributed over the whole length of the churn, it is more easily freed from its excess of water than if the whole butter collected in one sole mass, as happens with certain types of churning, wherein the butter rolls when it comes into contact with the walls and agglomerates into a lump, which retains the water, and the interior butter-granules do not stick together. Owing to the fact that this mass of butter is distributed over the whole length of the churn, the two extremities of the mass might, while the butter is falling, rub against the two bottoms of the churn if these latter were not concave. These fractions would have the disadvantage of deteriorating the butter-granules which would be injurious to the quality of the finished product and, moreover, this gliding would facilitate the sticking of the butter to the bottom.

The type of churn with cycloidal walls, while at the same time retaining the same advantages as the type with triangular profile, and while at the same time working in a similar way, permits, besides, accomplishing the following two supplementary results:

- (a) Increase of the rotational speed and of the rapidity of working,
- (b) More vigorous churning due to the projections 1.

From the point of view of the manufacture of such churning, it must be considered that the two bottoms are similar and can be pressed or obtained by any other means from a sheet formed of a single piece.

The pressing operation gives the parts 9—10 the concave shape towards the interior of the churn and forms the edges 15 parallel to the longitudinal axis of the churn; this edge permits welding the two bottoms to the body. The edges 15 are connected with the parts 16 by a recess which facilitates the interior cleansing of the churn.

The assembling of the two bottoms to the sheet of the body 7 takes place by exterior or interior welding according to the chosen mode of choking up the fissures which might exist after welding.

If interior welding is chosen, this is considerably facilitated by the absence of lateral walls between the extremities 2 of the sheets 1—7 of the body, because the opening of the churn extends over the whole length of the latter. There is consequently no welding to be carried out between the points 2' which form the opening. It would be otherwise if the opening had the usual dimensions adopted for the well-known churning wherein this opening has a length less than the length of the churn.

What I claim is:

1. A metallic churn and butter kneader, rotatable about the horizontal axis thereof, said churn and butter kneader comprising a substantially closed container consisting of two parallel end walls and a connecting side wall extending therebetween, said connecting side wall being shaped to have three distinct parts thereof, each part being shaped to approximate, in part, the outline of a separate cycloidal curve, and the terminal portion of each of said cycloidal curves being connected to the start of the next adjacent curve by a plane metallic connecting member, so positioned as to form an acute angle with a line extending tangentially to said terminal portion of the cycloidal curve to which it is joined, said cycloidal curves and said plane metallic connecting members together constituting said connecting side wall of said churn and butter kneader.

2. A metallic churn and butter kneader as defined in claim 1, wherein said cycloidal curves forming part of said connecting side wall of said churn and butter kneader are so positioned that all points on said curves deviate, to a greater and greater extent, from the horizontal axis of said churn and butter kneader as said curves progress from their starting points to their terminal points.
